TELEPHONE SYSTEM

Clarence E. Lomax, Oak Park, and John H. Voss, Downers Grove, Ill., assignors to Associated Electric Laboratories, Inc., Chicago, Ill., a corporation of Delaware

Application November 23, 1936, Serial No. 112,190

28 Claims.

(Cl. 179—5)

The present invention relates in general to telephone systems in which connections may be established through the medium of subscriber controlled selector and connector switches, but is more particularly concerned with a system of the above character which is combined with or has superimposed on it, so to speak, a fire alarm system; and the object of the invention may be said to be, broadly, the provision of new and improved auxiliary apparatus for use in connection with a telephone system.

In the preferred embodiment of the invention, means are provided whereby any telephone in the system may be used as a fire alarm station in addition to performing the functions usually ascribed to a telephone in an automatic system. When used as a fire alarm station the receiver of a given telephone is removed and a certain digit dialled in the usual manner, the receiver then being immediately restored to the switch hook. As a result of the foregoing a code representative of the location of the originating telephone is sounded upon an alarm circuit, and a permanent record is made thereof.

A feature of the invention relates to the employment of a finder switch as a means of associating any one of a plurality of fire alarm stations with the fire alarm transmitting equipment, thereby making the system more reliable and cheaper to install and maintain.

These and other objects and features, not specifically pointed out, will be apparent by referring to the accompanying drawings which together with the detailed description constitute the preferred embodiment of the invention.

The drawings comprising Figs. 1 to 4, inclusive, when arranged with Fig. 1 to the left of Fig. 4, with Fig. 2 below Fig. 4 and with Fig. 3 to the left of Fig. 2, show sufficient detail to enable a clear understanding of this invention.

In Fig. 1 is shown the automatic telephone stations A and A', which have the usual talking, signalling, and impulse sending instrumentalities. The line switches C and C' are mechanically of the well known rotary type in which the wipers have no normal position and move in a forward direction only.

The selector switch E is mechanically of the well known vertical and rotary type in which the bank contacts are arranged in horizontal rows or levels. The connector switch denoted by the dotted rectangle H is also a switch of the vertical and rotary type.

The holding bridge D is one of a number of such bridges which are seizable by the selector E

when the wipers of the said selector are raised to the ninth level of bank contacts. When a connection is extended to the holding bridge D, battery is supplied to the calling subscriber by the line relay 117, while a holding ground is provided by release relay 191.

A fire alarm relay, such as the relays R and R', is associated with each line switch in order that the telephone connected thereto may function as a fire alarm transmitting station.

In Fig. 2 is shown the finder switch FS which is of the vertical and rotary type having wipers 212 to 217, inclusive, which are moved first in a vertical direction and then in a rotary direction to find an operated fire alarm relay, such as the relay R of Fig. 1. Since, in the present embodiment of this invention, a finder switch of 200 point capacity is used, the finder FS is provided with two sets of wipers, the wipers 212, 214, and 216 forming the first set and wipers 213, 215, and 217 forming the second set. The finder switch FS is also equipped with a vertical test wiper 262. Switching relays 218 and 219 are of the type disclosed in Patent 1,673,884, issued June 19, 1928 to H. E. Pye. The cores of these switching relays are provided with two windings which are separated by a magnetic spacing member, a projection of which extends back and forms a back stop against which the armature of the relay rests. The winding on the heel end of the relay is the magnetizing coil, and the flux produced thereby traverses the path including this magnetic iron back stop, which is in shunt with the air gap, and no amount of current in this magnetic coil will cause the armature to operate. A very small current in the armature end winding of the relay, when in the same direction as the magnetizing winding, will cause the relay to operate. All relays of this type have been shown in the drawings with lugs extending from their center portion and such relays hereinafter will be referred to as "three pole relays".

As the finder switch FS is of only 200 point capacity it follows that a plurality of such finders must be provided in order that access may be had to all of the fire alarm relays, such as relay R of Fig. 1.

In Fig. 3 is shown a finder sequence switch SEQ—3 which functions to permit the operation of only one finder switch at a time. The sequence switch SEQ—3 is mechanically similar to the well known rotary line switch.

In Fig. 4 is shown a sender switch SEN—1 which functions to transmit a three digit fire alarm code, distinctive of a particular telephone

station, over the alarm circuit AC. A permanent record of the code is made by the conventional punch register PR.

The sender sequence switch SEQ-2 functions 5 to control the number of repetitions of the code and thereafter to release the initialing equipment.

The cross connecting frame CF provides means whereby the marker bank contacts, which are multiplied to all finder switches such as FS of 10 Fig. 2 may be cross connected to the marker banks of the sender switch SEN-1.

The sender switch SEN-1 and the sequence switch SEQ-2 are mechanically similar to the well known rotary line switch.

15

Operation of telephone system

The system having been described in general, a detailed description will now be given of its operation, and for this purpose it will be assumed that the subscriber at station A, Fig. 1, desires to call station A' whose number is assumed to be 236.

When the receiver is removed at the calling station, a circuit is closed over the line conductors 111 and 112 for the line relay 113 of the line switch C. Line relay 113, upon energizing, closes at armature 114 a circuit for switching relay 115 and operating magnet 116 in series, and at armature 117 connects the test wiper 120 to a point in the circuit between the switching relay 115 and the stepping magnet 116. From this point the operation depends upon whether the trunk line upon which the wipers of the line switch are standing is busy or idle. If it is busy there is ground potential on test contact 123, switching relay 115 is thereby short circuited, and operating magnet 116, which interrupts its own circuit, is operated in the manner of a buzzer to advance the switch wipers step by step in search of an idle trunk. In the present case, however, we shall assume that the trunk upon which the wipers of the line switch are standing is idle. That being the case switching relay 115 is not short circuited, and operating magnet 116 is not energized on account of the high resistance of switching relay 45 115. Switching relay 115, however, is energized and at armature 129 disconnects test wiper 120 from the point between its own winding and that of the operating magnet 116 and connects it to the grounded private normal conductor 130. Relay 115 also disconnects the line conductors 111 and 112 from the winding of relay 113 and ground respectively, and extends them by way of armatures 131 and 132 and their respective make contacts, wipers 118 and 121, bank contacts 109 and 55 124, trunk conductors 125 and 128, armatures 133 and 134 and their break contacts, to the upper and lower windings of the line relay 135 of the selector E. Line relay 135 now energizes over the calling subscriber's loop and at its armature 136 closes a circuit for the slow acting release relay 137 from ground at armature 146. Release relay 137, upon energizing, opens a point in the circuit of release magnet 138, prepares a circuit for relay 139 at armature 140, and at armature 141 places 60 ground upon release trunk conductor 142, thereby establishing a holding circuit for the line switch C. By means of this ground potential on test contact 123 and its multiples in the banks of the other line switches which have access to selector 65 E, the seized trunk is maintained busy in the usual manner. A branch of this holding circuit extends by way of private normal conductor 130, to multiple test contacts in the banks of the connector switches having access to the calling line, 70 thereby guarding it against intrusion in the usual 75

manner. It may be mentioned that a further result of the energization of switching relay 115 was the extension of the fire alarm conductor 126 to fire alarm relay R by way of armature 145 and its make contact.

The calling subscriber now operates his calling device in accordance with the first digit 2 of the desired number thereby producing two interruptions in the circuit of line relay 135 of the first selector E. As soon as relay 135 deenergizes in 10 response to the first of these interruptions a circuit is closed from ground at armature 146, armature 136 and its break contact, armature 140 and its make contact, through the series relay 139 and vertical magnet 147 to battery. Vertical magnet 15 147, upon energizing, raises the wipers 148, 149, and 150 to a position opposite the first level of bank contacts, whereupon the off normal springs 152 close and complete a circuit from the grounded release trunk conductor 142, by way of 20 armature 157 and its make contact, (relay 139 having energized), off normal springs 152, armature 158 and its break contact, through relay 153 to battery. Stepping relay 153, upon energizing, closes a point in the circuit of rotary magnet 154 25 at armature 155 and at armature 156 closes a locking circuit for itself independent of relay 139. When line relay 135 deenergizes in response to the second interruption produced in its circuit the vertical magnet 147 is again operated to raise the 30 wipers one step, thus bringing the wipers opposite the desired level of bank contacts. Relay 139, being slow acting, will remain energized while impulses are passing through it to the vertical magnet. Shortly after the last vertical impulse relay 139 will deenergize and close a circuit through the rotary magnet 154 at armature 157. Rotary magnet 154, upon energizing, advances the wipers 148, 149, and 150 into engagement with the first set of contacts in the second level, and at 40 armature 158 opens the circuit of stepping relay 153. Stepping relay 153, upon deenergizing, opens another point in its circuit, and at armature 155 opens the circuit of rotary magnet 154. Rotary magnet 154, upon deenergizing, again prepares the circuit of stepping relay 153. From this point the operation depends upon whether the trunk terminating in the first set of contacts is 45 busy or idle. If it is busy, the stepping relay 153 energizes again over the following circuit; from ground by way of the test contact with which test wiper 149 is in engagement, test wiper 149, armature 161 and its break contact, off normal springs 152, armature 158 and its break contact, through relay 153 to battery. Stepping relay 153, upon energizing, closes a locking circuit for itself at armature 156 and at armature 155 again completes the circuit of rotary magnet 154. This alternate operation of the stepping relay 153 and the rotary magnet continues so long as test wiper 60 149 engages grounded contacts. In this case we will assume that the trunk line comprising conductors 197, 198, and 199 is the first found to be idle. That being the case, when the wipers of selector E arrive upon bank contacts 162, 163 and 65 164 there is no ground on test contact 163 and consequently stepping relay 153 does not again energize. With this condition existing switching relay 159 energizes over the following circuit; from ground by way of release conductor 142, 70 switching relay 159, off normal springs 152, armature 158 and its break contact, through relay 153 to battery. Stepping relay 153 does not energize over this circuit on account of the high resistance of switching relay 159. Relay 159, upon 75

energizing, removes ground from the circuit of relay 137 at armature 146, disconnects test wiper 149 from the point between switching relay 159 and stepping relay 153 and connects it to ground by way of release trunk conductor 142 at armature 161, thus making the seized trunk busy immediately, and at armatures 133 and 134 disconnects the trunk conductor 125 and 128 from line relay 135 and extends them by way of the make contacts of the said armatures, wipers 148 and 150, bank contacts 162 and 164, trunk conductors 197 and 199 to the line relay of connector H. Connector H thereupon places ground upon the release trunk conductor 198, thus establishing the usual holding circuit for selector E and the line switch C, before the slow acting release relay 137 of the selector E has had time to deenergize. When the calling subscriber operates his calling device in accordance with the second digit 3 of the desired number, the connector H will raise its wipers to a position opposite the third level of bank contacts. The calling subscriber now dials the final digit 6 of the desired number, whereupon the connector rotates its wipers six steps 25 into connection with the line extending to the station A'. Upon the completion of the connection to the called line a signalling circuit is established in the usual manner and the bell at the called station is operated to notify the subscriber that he is wanted. When the called party answers, the conversation will proceed as desired, and when the conversation is complete the calling subscriber will replace his receiver, bringing about the release of the connection in the usual 35 manner.

Fire alarm initiation

An explanation will now be given of the fire alarm transmitting equipment. The subscriber, when wishing to originate a fire alarm at station A, will first remove the receiver, whereupon the line switch C will operate in the usual manner to extend the connection to a first selector, it being assumed that the selector E is the one first found to be idle. The subscriber next dials the digit 9, 40 and as a result thereof the selector E raises the wipers 148, 149, and 150 to a position opposite the ninth level of bank contacts. The selector next selects an idle trunk in this level, and it will be assumed that the trunk comprising conductors 45 187, 188, and 189 is the one first found to be idle. The switching relay 159 of the selector E, upon energizing, disconnects the trunk conductor 125 and 128 from line relay 135 and extends them by way of make contacts of armatures 133 and 134, 50 wipers 148 and 150, bank contacts 192 and 193, conductors 189 and 187, through the double wound relay 190 of the holding bridge D, to battery and ground, respectively. The line relay 190, upon energizing, closes the circuit of release relay 191 at armature 173, and the latter relay, upon energizing, places ground upon the release trunk conductor 188 at armature 174, thereby establishing the usual holding circuit for the selector E and the line switch C. A further result 55 of the energization of relay 191 is the closing of a circuit from ground at armature 175, break contact and armature 176, through relay 177 to battery. Relay 177, upon energizing, opens its own circuit and will therefore operate as a buzzer as long as armature 175 remains operated. This 60 buzzer action of relay 177 produces a tone which is placed on the negative line by way of condenser 178 and conductor 187.

This tone is audible in the receiver at station A and advises the subscriber that the de-

sired fire alarm has been initiated. The subscriber then restores his receiver, whereupon the release of the switches involved in this connection takes place in the usual manner.

Returning to a consideration of selector E at the time of the energization of switching relay 159, the above mentioned operation results in the deenergization of line relay 135 followed after a time by the release of the slow acting release relay 137. During the interval of time elapsing between the energization of relay 159 and the deenergization of relay 137 a circuit may be traced as follows: from ground at armature 146 and its make contact, armature 171 and its make contact, springs 172 which are closed by the shaft 15 only when raised to the ninth level, conductor 126, bank contact 122, wiper 119, make contact and armature 145, through fire alarm relay R and resistance 182 to battery.

Fire alarm transmission

From the foregoing discussion it is apparent that the fire alarm system comprises a plurality of fire alarm relays, such as relay R of Fig. 1, and that more than one of said relays may be energized simultaneously.

The fire alarm transmitting apparatus consists of the single sender SEN—1 of Fig. 4, and the associated sequence switch SEQ—2.

In order that the single fire alarm sender may become associated with one of a plurality of fire alarm relays, it has been necessary to introduce a finder system comprising a plurality of finder switches such as FS of Fig. 2. As previously stated, each finder switch has access to only two hundred fire alarm relays, it follows then that the purpose of the finder sequence switch SEQ—3 is to permit but one finder to operate at a time and thereby associate, for the time being, one fire alarm relay with the common fire alarm sender.

For the purpose of explanation we will assume that station A of Fig. 1 has been assigned the number 222, and that finder switch FS of Fig. 2 serves the first and second hundred lines. Mention may be made here that the various finders are associated in order with the bank contacts of the finder sequence switch SEQ—3, and that each contact in the bank accessible to wiper 302 (the finder bank) is normally grounded through break springs on the start relay of the particular finder associated therewith.

Returning now to a consideration of the previously described energization of relay R of Fig. 1, we find that a circuit may be traced from ground at armature 181, conductor 200, resistance 201 (common to 20 relays such as relay R), through start relay 202 to battery (the latter relay is common to 200 relays such as relay R). Relay 202, upon energizing, removes ground, at armature 203, from the contact associated with finder FS in the finder bank of the finder sequence switch SEQ—3.

A further result of the energization of start relay 202 is the placing of ground on the common kick off circuit of sender sequence switch SEQ—3, the circuit may be traced from ground at armature 203 and its make contact, conductor 300, normal bank contact 301, wiper 302, armature 303 and its break contact, through self interrupting springs and operating magnet 304 to battery. The operating magnet 304 will now energize, open its own circuit, and deenergize to advance wipers 302, 324, 316, and 329 into engagement with the first contact in the banks associated therewith.

The operation now depends upon whether the

start relay of the first finder switch is energized or not. If it is not energized a circuit may be traced from ground at armature 203 and its break contact, break contact and off normal spring 204, break contact and armature 205, conductor 305, bank contact 306, wiper 302, armature 303, through self interrupting springs and operating magnet 304 to battery. The operating magnet will now energize and act as a buzzer to advance 10 the wipers of the sender sequence switch step by step so long as wiper 302 engages grounded bank contacts.

In the present case we have shown start relay 202 to be energized at the time that wiper 302 engaged bank contact 306, and it follows that there will be no further rotation at this time.

A further result of the energization of start relay 202 is the closing of a circuit from ground at armature 206 and its make contact, conductor 307, through relay 308 to battery. Relay 308 will now energize and light the busy lamp 309, and will also close a circuit from ground at armature 310 and its make contact, make contact and armature 311, relay 312, through self interrupting springs 25 and operating magnet 304 to battery. The operating magnet will not energize at this time because of the high resistance of relay 312.

Relay 312 will now energize and prepare a circuit for the operating magnet 304 at armature 303; provide a locking circuit for itself at armature 320; prepare a circuit for the lower winding of relay 321 at armature 322; and close a circuit from ground at armature 323, wiper 324, bank contact 325, conductor 326, through relay 220 to negative battery. Relay 220 will now energize and close the polarizing circuit of the three-pole relays 218 and 219 at armature 227, this, as previously explained, will not cause the operation of said relays.

A further result of the energization of relay 312 is the closing of a circuit from ground at armature 313, break springs controlled by armature 314, armature 315 and its break contact, wiper 316, break contact 317, conductor 207, through vertical magnet 208 to battery. The vertical magnet will now energize and raise test wiper 262 and wipers 212 to 217, inclusive, to a position opposite the first level of bank contacts; at the same time closing a circuit from ground at armature 209, conductor 318, through relay 319 to negative battery. Relay 319, upon energizing, will open the circuit to the vertical magnet 208 at break contacts controlled by armature 314, whereupon the vertical magnet deenergizes and at armature 209 opens the circuit to relay 319. The deenergization of relay 319 again closes the circuit of the vertical magnet 208, whereupon the wipers of the finder are advanced another vertical step. This interaction between the vertical magnet 208 and relay 319 takes place in the manner just described until the test wiper 262 of the finder FS finds marking ground applied to a vertical bank contact.

As previously explained, the second vertical bank contact is grounded by relay R of Fig. 1, and when that contact is engaged by wiper 262, ground thereon is extended by said wiper, conductor 327, bank contact 328, wiper 329, armature 330 and its break contact, lower winding of relay 321, make contact and armature 322, through relay 319 to battery. It follows then that relay 319 will not deenergize when its circuit is opened by the subsequent deenergization of the vertical magnet 208, thus the vertical stepping ceases. Relay 321 will now energize

sufficiently to lock its upper winding, by way of make contact and armature 331 to ground at armature 313; the circuit of its lower winding, and of relay 319, will be opened at armature 330 when the relay becomes fully operated as the result of the energization of its upper windings. 5

A further result of the energization of relay 321 and the deenergization of relay 319, is the closure of a circuit from ground at armature 313, break contacts controlled by armature 314, armature 315, and its make contact, conductor 221, make contact and armature 222, break contact and armature 223, break contact and armature 224, through rotary magnet 225 to battery. Rotary magnet 225, upon energizing, rotates the 10 wipers 212 to 217, inclusive, into engagement with the first set of bank contacts in the second level, and rotates the vertical test wiper 262 out of engagement with the vertical bank. At armature 226, rotary magnet 225 completes a circuit for 15 relay 319 over conductor 318. At this point further rotation of the wipers of the finder switch FS is dependent upon whether the test wipers 216 and 217 encounter ground or not. In case ground is not on either of the bank contacts with which 20 the test wipers are in engagement, neither of the switching relays 218 or 219 will energize. Therefore, as the rotary magnet 225 causes the 25 energization of relay 319, and the latter relay in turn opens the circuit of the rotary magnet, a cycle of operations is set up which results in the step-by-step operation of the rotary magnet until one of the test wipers 216 or 217 encounters a 30 grounded bank contact.

Owing to the fact that fire alarm relay R (whose 35 number assignment was assumed to be 222) is energized, test wiper 216 will find ground on the second bank contact in the second level. At that time a circuit for the three-pole switching relay 218 may be traced from ground at armature 180 40 and its make contact, conductor 229, bank contact 230, test wiper 216, through the operating winding of switching relay 218 to negative battery at make contact and armature 228. The current now flowing through the operating winding of 45 switching relay 218 is in a direction to assist that flowing through the polarized winding, and, as a result, the switching relay energizes very quickly to open the circuit of rotary magnet 225 at armature 224. 50

A further function of switching relay 218 is to establish marking points in the banks of the sender switch SEN-1 so that the code 222 distinctive of telephone station A, will be retransmitted over the alarm circuit AC. In accordance 55 with the assumption that finder switch FS serves the first and second hundred lines, armature 231 of relay 218 has been connected by way of conductor 236 and jumper 432 of cross connecting frame CF to bank contact 431 in the bank served by wiper 407, thereby establishing 2 as the hundreds digit of the code. To digress for a moment, it may be said that, had the finder FS searched for and found the fire alarm relay associated with telephone station 122, the physical 60 movement of its wipers would have been the same as that previously described, but in the latter case relay 219, instead of relay 218 would have energized. Therefore the make contact of armature 232 of relay 219 has been connected by way of 65 conductor 235 and jumper 465 of cross connecting frame CF to bank contact 466 in the bank served by wiper 407, thereby establishing 1 as the hundreds digit of the code. The tens and units digits being the same for corresponding numbers in 70 75

each hundred, it follows that bank contact 233 may be cross connected to establish the units digit of the code and that bank contact 234 may be cross connected to establish the tens digit of 5 the code. Therefore bank contact 233 has been connected by way of conductor 239 and jumper 445 of cross connecting frame CF to bank contact 444 in the bank served by wiper 447. Bank contact 234 has been connected by way of conductor 10 237 and jumper 442 of cross connecting frame CF to bank contact 441 in the bank served by wiper 407.

Relay 218, upon energizing, closes a circuit from ground, through high resistance relay 401, conductor 400, armature 243, and its make contact, make contact and armature 205, conductor 385, bank contact 306, wiper 302, armature 303 and its make contact through operating magnet 304 to battery. The operating magnet cannot energize 20 at this time because of the high resistance of relay 401. The last mentioned relay will, however, energize and close a circuit from ground at armature 402 and its make contact, armature 403 and its break contact, through relay 404 to 25 negative battery. Relay 404, upon energizing, will close a circuit from ground at armature 405 and its make contact, make contact and armature 406, wiper 401, bank contact 408, make contact and armature 409, through relay 410 and 30 resistance 411 to battery. Relay 410 will now energize and lock itself up to ground at armature 405 by way of armature 412 and its make contact. Relay 410 also prepares the circuit of 35 coding relay 428 at armature 427.

40 A further result of the energization of relay 404 is the closing of a start circuit to the interrupter relay group comprising relays 415, 418, 421, and 426, the circuit may be traced from ground at armature 405 and its make contact, armature 413 and its break contact, through relay 415 to battery. Relay 415 now energizes and at armature 416 extends the start circuit to relay 418. Relay 418 next energizes and at armature 419 extends the start circuit to relay 421. 45 Relay 421 thereupon energizes and extends the start circuit by way of armature 422 and its make contact, armature 423 and its break contact, armature 425 and its break contact, through relay 426 to battery. Relay 426 will now energize 50 and open the circuit of relay 415 at armature 413. Relay 415 will next deenergize and open the circuit of relay 418 at armature 416. Relay 418 thereupon deenergizes and opens the circuit of relay 421 at armature 419. Relay 421 then deenergizes and opens the circuit of relay 426 at armature 422. Relay 426 finally deenergizes and again closes the circuit to relay 415 at armature 55 413, whereupon the cycle is repeated and the interrupter continues to function so long as the start circuit is grounded by armature 405.

60 At each energization of relay 421 a circuit, in parallel with armature 425 and relay 426, is closed through operating magnet 424 to negative battery, therefore wipers 447, 407, 438, and 467 are advanced step-by-step under control of the 65 aforementioned interrupter relays. At each energization of relay 426 the grounded start circuit is extended by way of armature 413 and its make contact, make contact and armature 427, through 70 coding relay 428 to battery. It follows then that at each cycle of the aforementioned interrupter relays the coding relay 428 will energize and impress current from generator G on the alarm circuit AC by way of armature 430 and its make contact, thus causing the operation of all ringers 75

bridged across that circuit, such as ringer R. A further result of the energization of coding relay 428 is the closing, at armature 429 and its make contact, of a circuit through the conventional punch register PR.

At the second step of the sender switch SEN—1 the first marked contact is reached and a circuit may be traced from ground at armature 405 and its make contact, make contact and armature 406, wiper 401, bank contact 431, jumper 432, 10 conductor 236, armature 231 and its make contact, break contact and armature 232, conductor 433, make contact and armature 434, through relay 435 to negative battery. As the wipers of the sender switch SEN—1 advance upon the de-energization of the operating magnet 424 it follows that relay 435 will energize in time to prevent the further operation of the operating magnet 424 by the open circuit at armature 423. Further operation of relay 426 will be prevented 15 by the open circuit at armature 425. A circuit is also closed from ground at armature 436, armature 437 and its make contact, through resistance 411 to battery. The latter traced circuit serves to shunt relay 410, which will now de-20 energize and open the circuit to coding relay 428. 25

As a result of the foregoing operations it will be seen that the coding relay 428 has twice energized and thus impressed upon the alarm circuit AC, and the punch register PR, the hundreds 30 digit of the code 222.

35 A further result of the energization of relay 435 is the closure of a restoring circuit extending from ground at bank contact 468, wiper 438, armature 439 and its make contact, through self 40 interrupting springs and operating magnet 424 to battery. It is further to be noted that relay 435 locks itself to this restoring circuit by way of armature 440 and its make contact. The operating magnet will now energize, open its own 45 circuit, and continue to function as a buzzer to advance the associated wipers step by step so long as wiper 438 engages grounded contacts. When bank contact 440 is reached by wiper 438 the self interrupted rotation will cease, and 50 shortly thereafter slow-to-release relay 435 will deenergize and again close the relay interrupter circuit to the operating magnet 424 and to relay 426. The next pulse to the operating magnet 424 will cause wiper 407 to advance into engagement 55 with bank contact 469, at which time the circuit of relay 410 in series with resistance 411 will again be closed, with the result that the latter relay will energize, lock up to ground on the start conductor and again prepare the circuit of coding relay 428. The time interval introduced by the circuit operations just described provides the required interval between the transmission of the first and second digits of the code 222.

60 Subsequent cycles of the interrupter will cause the advancement of the wipers of the sender switch SEN—1 and the further operation of coding relay 428. The second marking point will be reached when wiper 407 engages bank contact 441, thereby completing a circuit to relay 435 by 65 way of jumper 442, conductor 237, bank contact 234, wiper 213, make contact and armature 238, conductor 433, and make contact and armature 434. Relay 435 will function as before to stop the interrupter, to shunt relay 410, and to 70 close the restoring circuit of operating magnet 424. As a result of the foregoing it will be seen that the coding relay 428 has twice energized and thus impressed upon the alarm circuit AC, and the punch register PR, the tens digit of the 75

code 222. When bank contact 443 is reached by wiper 438 the self interrupted rotation will cease, relay 435 will deenergize and again close the relay interrupter circuit to the operating magnet 424, and to relay 426. The next pulse to the operating magnet will cause wiper 447 to advance into engagement with bank contact 470, at which time the circuit of relay 410 in series with resistance 411 will again be closed, with the result that the latter relay will energize, lock up to ground on the start conductor and again prepare the circuit of coding relay 428. The time interval introduced by the circuit operations just described provides the required interval between the transmission of the second and third digits of the code 222.

Subsequently cycles of the interrupter will cause the advancement of the wipers of the second switch SEN-1 and the further operation of coding relay 428. The third marking point will be reached when wiper 447 engages bank contact 444, thereby completing a circuit to relay 435 by way of jumper 445, conductor 239, bank contact 233, wiper 212, make contact and armature 240, conductor 433 and armature 434. Relay 435 will function as before to stop the interrupter, to shunt relay 410, and to close the restoring circuit of operating magnet 424. As a result of the foregoing, it will be seen that the coding relay 30 428 has twice energized and thus impressed upon the alarm circuit AC, and the punch register PR, the units digit of the code 222. When bank contact 471 is reached by wiper 467 the self interrupted rotation will cease, relay 435 will deenergize and again close the relay interrupter circuit to operate magnet 424 and to relay 426. The wipers of the sender switch SEN-1 will continue to advance in response to the operation of the relay interrupter, and as wiper 447 passes over bank contact 446 a pulse of current is passed to the operating magnet 448 of the sender sequence switch SEQ-2. The latter magnet will respond thereto and advance wipers 453 and 454 one step, but without effect at this time. The time interval introduced by the circuit operations just described provides the required interval between the first and second rounds, or repeats, of the code 222.

When wiper 407 of the sender SEN-1 next engages bank contact 408 the circuit will again be closed to relay 410, and thus will start the transmission of the second and final round of the code 222. This operation need not be described in detail, as it is merely a repetition of what has gone before, and it will suffice to point out that the next pulse of current by way of wiper 447 and bank contact 446 will cause the operating magnet 448 of the finder sequence switch SEQ-2 to advance the associated wipers one step. A circuit is now closed from ground at wiper 454, bank contact 455, through relay 456 to battery. Relay 456, upon energizing, closes a circuit from ground at armature 461 and its make contact, conductor 462, armature 242 and its break contact, make contact armature 241, wiper 214, bank contact 299, conductor 183, through resistance 182 to battery. The foregoing circuit is in shunt of fire alarm relay R and results in the deenergization of said relay; thereby positive potential marking is removed from bank contacts 230 and 249, and the circuit to start relay 202 is opened. Start relay 202 now deenergizes and opens the circuit of relay 308 which, in turn, deenergizes and extinguishes the lamp 309.

A further result of the energization of relay 456 is the shunting of relay 401 at armature 460, thereby causing the complete energization of operating magnet 304 of finder sequence switch SEQ-3. Operating magnet 304 will open the circuit of relay 312 at the self interrupting contacts of said operating magnet, whereupon relay 312 will deenergize and, by virtue of armature 303, will transfer wiper 302 from the terminal of the operating magnet 304 to the break spring of 10 self interrupting contact associated with the said operating magnet. The operating magnet 304 will now deenergize and advance the associated wipers one step and, upon the assumption that no other fire alarm relay, connected to the relay R 15 of Fig. 1, is energized at this time, wiper 302 will engage grounded bank contacts and operating magnet 304 will function as a buzzer to advance the associated wipers step by step to the normal position shown in Fig. 3. A further result of 20 the deenergization of relay 312 is the opening of the locking circuit of relay 321, whereupon the latter relay deenergizes. The sender sequence switch SEQ-3 is now in normal position and awaits the next energization of a fire alarm relay. 25

The deenergization of relay 312 and the subsequent advancement of the sender sequence switch wipers will result in the deenergization of relay 220 of the finder switch FS, whereupon the circuit to the polarizing winding of relays 218 and 219 30 is opened at armature 227, and the battery feed to the operating winding of the same relays is opened at armature 228. Relay 218 now deenergizes. A further result of the deenergization of relay 220 is the closing of a circuit 35 from ground at armature 227 and its break contact, off normal spring 244 and its make contact, armature 245 and its break contact, break contact and armature 246, release magnet 247 in parallel with resistance 248, conductor 332, 40 through relay 333 to battery. Relay 333 will energize and close the circuit of lamp 334, and at the same time the release magnet 247 will energize and cause the shaft and wipers 212 to 45 217, inclusive, and test wiper 262 to return to normal position, its own circuit being opened when the shaft reaches normal position because of the off normal springs ONS. The finder switch FS is now in normal position and awaits the next seizure by the sender sequence switch SEQ-3. 50

It may be mentioned in passing that the release of the finder switch FS would occur as described even though one or more fire alarm relays associated therewith might be energized at the time that relay R of Fig. 1 deenergizes. 55 The springs indicated at reference 250 are actuated by the shaft only in the event that eleven rotary steps are taken. The advance of the sender sequence switch SEQ-3 and the release of the finder switch FS would occur as the result 60 of such an unstandard operation.

Returning now to a consideration of the sender sequence switch SEQ-2, it will be seen that relay 401, upon deenergizing, opens the circuit of relay 404 which, in turn, deenergizes and removes 65 ground from the relay interrupter start circuit at armature 405, and at the break contact of the same armature completes a restoring circuit by way of bank contact now engaged by wiper 467, said wiper, break contact and armature 434, 70 through relay 435 to battery. Relay 435 will now operate and extend its energizing circuit by way of armature 439 and its make contact, through self interrupting springs and motor magnet 424 to battery. The operating magnet will now en- 75

ergize, interrupt its own circuit, and function as a buzzer to advance the associated wipers step by step so long as wiper 467 engages grounded bank contacts. When wiper 438 engages bank contact 5 473 the rotation will cease, shortly thereafter relay 435 will deenergize and the sender will again be in normal position awaiting the next seizure by a finder switch such as the finder switch FS of Fig. 2.

10 A still further result of the energization of relay 456 is the closing of a circuit from ground at armature 449 and its make contact, high resistance 450, relay 451, in parallel with resistance 452, bank contact 472, wiper 453, through self interrupting contact and operating magnet 448 to battery. The operating magnet 448 will not energize at this time because of the high resistance 450, relay 451 will, however, energize and provide a locking circuit for relay 456 at armature 15 458. A further function of relay 451 is to shunt resistance 450 at armature 457, whereupon the operating magnet 448 will energize in series with relay 451, will open its own circuit, and operate as a buzzer to advance the associated wipers step 20 25 by step so long as wiper 453 engages contacts multiplied to relay 451. When wiper 453 engages bank contact 463 the rotation will cease, and shortly thereafter relay 451 will deenergize and open the locking circuit of relay 456. It may be 30 mentioned here that bank contact 463 is only one of the five "normal" positions which may be assumed by wiper 453.

Key K—4 and relay 464 provide means whereby a second sender, whose marker banks are in 35 multiple with those of sender SEN—1, may be placed in service in the event of the failure of sender SEN—1.

While the invention has been shown as a combined telephone and fire alarm system, it will be 40 understood that the signalling system could be utilized equally as well for other purposes, as for instance, messenger call, police signalling, a watchman's service.

The object and scope of this invention having 45 been described, what is considered to be new and what is desired to have protected by Letters Patent, will be pointed out more specifically in the appended claims.

What is claimed is:

- 50 1. In a combined telephone and signalling system, a central exchange, a plurality of subscribers' lines extending to said exchange, means included in said exchange and controlled over a calling one of said subscribers' lines for establishing a telephone connection between said calling subscriber's line and a called subscriber's line, code transmitting equipment included in said exchange and comprising a plurality of finder switches, an alarm relay associated with each 55 of said subscribers' lines, means controlled over any calling one of said subscribers' lines for operating the alarm relay associated with the calling line, means responsive to the operation of said alarm relay for initiating the operation of said code transmitting equipment, an alarm circuit extending to said exchange, and means controlled by said code transmitting equipment for transmitting over said alarm circuit a code identifying the calling subscriber's line.
- 60 2. In a combined telephone and signalling system, an exchange, a plurality of subscribers' lines extending to said exchange, means in said exchange and comprising a plurality of automatic switches for establishing telephone connections between said subscribers' lines, code transmitting equipment, finder switches includ-
- 65 70 75

mitting equipment in said exchange and comprising a plurality of finder switches, means controlled over a calling one of said subscribers' lines for establishing a connection between the calling line and said code transmitting equipment, said connection extending by way of at least a portion of said automatic switches, means individually associated with each of said subscribers' lines for causing said code transmitting equipment to generate a coded signal identifying the associated subscriber's line, an alarm circuit extending to said exchange, and means controlled by said code transmitting equipment for transmitting over said alarm circuit a coded signal corresponding to any calling one of said lines. 10 15

3. In a combined telephone and signalling system, an exchange, a plurality of subscribers' lines extending to said exchange, means included in said exchange and comprising a plurality of automatic switches for establishing telephone 20 connections between said lines, code transmitting equipment in said exchange and comprising a plurality of finder switches, holding means accessible to a portion of said automatic switches, means controllable over any one of said subscribers' lines for initiating the operation of said holding means, means individually associated with each of said subscribers' lines for initiating the operation of said code transmitting equipment, means responsive to the operation of said holding means for causing the operation of said last-named means, and means responsive to the operation of said code transmitting equipment for transmitting a coded signal identifying the calling line. 25 30 35

4. In a combined telephone and signalling system, an exchange, a plurality of subscribers' lines extending to said exchange, means including a plurality of automatic switches for establishing telephone connections between said lines, code transmitting equipment in said exchange and comprising a plurality of finder switches, means individually associated with each of said lines for initiating the operation of said code transmitting equipment, holding means accessible to said subscribers' lines, means including a portion of said automatic switches for establishing a connection between a calling one of said lines and said holding means and for causing the operation of said holding means, and means responsive to the operation of said holding means for initiating the operation of said second-named means. 40 45 50

5. In a combined telephone and signalling system, an exchange, a plurality of subscribers' lines extending to said exchange, means comprising a plurality of automatic switches for establishing telephone connections between said lines, code transmitting equipment in said exchange, relays individually associated with said subscribers' lines and each operative to initiate the operation of said code transmitting equipment, each of said relays being operative to mark the associated line in one of said finder switches, whereby said code transmitting equipment is rendered operative to transmit a coded signal identifying the said associated line, and means including said automatic switches for causing the operation of said relays. 60 65

6. In a signalling system, a plurality of lines each identified by a certain code designation, a plurality of control means, a series of selecting switches controllable over any one of said lines to select an idle one of said control means, code transmitting equipment, finder switches includ-

70 75

13. In a combined signalling and telephone system, a central exchange, automatic switches in said exchange, a plurality of lines extending to said exchange and terminating in said automatic switches, code signalling equipment in said exchange, finder switches included in said code signalling equipment, means controlled over any calling one of said lines for causing the operation of said automatic switches to establish a telephone connection between the calling line and a called one of said lines, means controlled over any calling one of said lines for causing said automatic switches to establish a connection between the calling line and said signalling equipment, means in said equipment and responsive to the connection of any calling line therewith for generating a code individual identifying the calling line, and means for transmitting said code from said exchange.
14. In a combined telephone and signalling system, a central exchange, automatic switches in said exchange, a plurality of substation lines extending to said exchange and terminating in said automatic switches, substations connected to said lines, code signalling equipment in said central exchange, finder switches included in said code signalling equipment, means controlled from a calling one of said substations for operating the automatic switches to establish a telephone connection between the calling substation and a called substation, said means being operative to control the automatic switches in accordance with a predetermined number to establish a connection between the calling substation and said signalling equipment, means in said signalling equipment and responsive to the connection of a substation therewith for generating a signal identifying the calling substation, and means operative to transmit said signal from said exchange regardless of whether the calling substation has been released from its connection with the signalling equipment.
15. In a combined telephone and signalling system, a central exchange, a plurality of substations connected to said exchange, code signalling equipment in said exchange, finder switches included in said code signalling equipment, means in said exchange controlled from a calling substation for establishing a telephone connection between the calling substation and any desired called substation, said means being controllable from any calling substation to establish a connection between the calling substation and said signalling equipment, means for transmitting a signal to the calling substation when such signalling connection is established whereby the connection may be immediately released at the calling substation, means included in said signalling equipment and responsive to the connection of a calling substation therewith for generating a signal identifying the calling substation, and means for then transmitting said last-named signal independently of the continued connection of the calling substation with said equipment.
16. In a combined telephone and signalling system, a central exchange, substations connected to said exchange and each including an impulse sender, code signalling equipment at said exchange, finder switches included in said signalling equipment, means responsive to the operation of the impulse sender at a calling substation in accordance with the designation of a called substation for establishing a telephone connection between the calling and called substations, means responsive to the operation of the impulse sender at a calling station in accordance with a predetermined designation for establishing a connection between the calling substation and said signalling equipment, means included in said signalling equipment and responsive to the connection of a substation there for generating a signal identifying the calling substation, means for indicating to the calling substation that the connection with the signalling equipment is established so that the connection may be released if desired, and means in said signalling equipment for transmitting the signal identifying the calling substation from said central exchange.
17. In a combined telephone and signalling system, a central exchange, substation lines extending to said exchange, a series of automatic switches in said exchange controllable over said substation lines to establish telephone connections between the substation lines, code signalling equipment in said exchange, means for controlling the automatic switches over any calling one of said lines to establish a connection between the calling line and said signalling equipment, a circuit connection extending from the connected substation line to said code signalling equipment exclusive of said automatic switches, and means in said signalling equipment controlled over said circuit connection for initiating the generation of a code individually identifying the calling substation.
18. In a combined telephone and signalling system, a central exchange, substation lines terminating in said exchange, automatic switches controllable over any calling one of said lines for establishing a telephone connection between the calling line and a called line, code signalling equipment in said exchange, finder switches included in said code signalling equipment, a circuit connection extending from the terminating end of each substation line to said signalling equipment, means for controlling the automatic switch over any calling substation line to extend a connection from said calling line to said signalling equipment, means responsive to the establishing of said last-named connection for energizing said circuit connection to initiate the operation of said signalling equipment to generate a signal identifying the calling line, and means in said signalling equipment and including one of said finder switches for transmitting said code.
19. In a combined telephone and signalling system, an exchange, a plurality of subscribers' lines extending to said exchange, said lines being arranged in groups, means including a plurality of automatic switches located in said exchange for establishing telephone connections between said lines, each of said switches being operable to a plurality of positions, a plurality of auxiliary automatic switches, each of said auxiliary switches corresponding to a particular group of said lines and each having a plurality of positions individually corresponding to the individual lines of the corresponding group, means responsive to the operation of one of said first-named plurality of switches to a predetermined position for selecting a predetermined one of said auxiliary switches and for causing the selected switch to operate to a predetermined one of its said positions, a signal transmitter adapted to transmit signals of different characteristics individually corresponding to the various positions of each of said auxiliary switches, and means responsive to the operation of any one of said auxiliary switches to any one of its said positions.

tions for causing said code transmitter to transmit the signal corresponding to the said one position.

20. In a combined telephone and signalling system, an exchange, a plurality of subscribers' lines extending to said exchange, said lines being arranged in groups, means including a plurality of automatic switches for establishing telephone connections between said lines, each of said switches being adapted to be taken for use by a calling one of said lines and being operative to a plurality of positions, a plurality of auxiliary automatic switches, each of said auxiliary switches corresponding to a particular group of said lines and each having a plurality of positions individually corresponding to the individual lines of the corresponding group, means comprising a selector switch commonly associated with all of said lines and responsive to the operation of one of said first-named plurality of switches to a predetermined position for selecting the one of said auxiliary switches which corresponds to the calling line responsible for the operation of said one of said first-named switches, means responsive to the selection of said one auxiliary switch for causing the operation thereof to a predetermined position corresponding to the last-named calling line, a signal transmitter adapted to transmit signals of different characteristics individually corresponding to the positions of each of said auxiliary switches, and means responsive to the operation of said one auxiliary switch to said predetermined position for causing said code transmitter to transmit the signal corresponding to the said predetermined position.

21. In a combined telephone and signalling system, an exchange, a plurality of subscribers' lines extending to said exchange, said lines being arranged in groups, means including a plurality of automatic switches for establishing telephone connections between said lines, each of said switches being adapted to be taken for use by a calling one of said lines and being operative to a plurality of positions, holding means arranged to be operated in response to the operation of any one of certain of said switches to a predetermined position, a plurality of auxiliary automatic switches, each of said auxiliary switches corresponding to a particular group of said lines and each having a plurality of positions individually corresponding to the individual lines of the corresponding group, means comprising a selector switch commonly associated with all of said lines and responsive to the operation of said holding means for selecting the one of said auxiliary switches which corresponds to the calling line responsible for the operation of said holding means, means responsive to the selection of said one auxiliary switch for causing the operation thereof to a predetermined position corresponding to the last-named calling line, a signal transmitter adapted to transmit signals of different characteristics individually corresponding to the positions of each of said auxiliary switches, and means responsive to the operation of said one auxiliary switch to said predetermined position for causing said code transmitter to transmit the signal corresponding to the said predetermined position.

22. In a combined telephone and signalling system, an exchange, a plurality of subscribers' lines extending to said exchange, said lines being arranged in groups, means including a plurality of automatic switches for establishing telephone

connections between said lines, each of said switches being adapted to be taken for use by a calling one of said lines and being operative to a plurality of positions, holding means arranged to be operated in response to the operation of any one of certain of said switches to a predetermined position, a relay individually associated with each of said lines and operative in response to the operation of said holding means only when the associated line is the calling line responsible for the operation of said holding means, a plurality of auxiliary automatic switches, each of said auxiliary switches corresponding to a particular group of said lines and each having a plurality of positions individually corresponding to the individual lines of the corresponding group, means comprising a selector switch commonly associated with all of said lines and responsive to the operation of any one of said relays for selecting the one of said auxiliary switches which corresponds to the group of lines including the line with which said one relay is associated, means responsive to the selection of said one auxiliary switch for causing the operation thereof to a position corresponding to the line associated with said one relay, a signal transmitter adapted to transmit signals of different characteristics individually corresponding to the positions of each of said auxiliary switches, and means responsive to the operation of said one auxiliary switch to said predetermined position for causing said code transmitter to transmit the signal corresponding to the said predetermined position.

23. In a combined telephone and signalling system, an exchange, a group of subscribers' lines extending to said exchange, means including a plurality of automatic switches for establishing telephone connections between said lines, an auxiliary automatic switch having positions individually corresponding to individual ones of said lines, means responsive to the operation of one of said plurality of switches to a predetermined position for causing said auxiliary switch to operate to one of its said positions, a signal transmitter adapted to transmit coded signals of different characteristics individually corresponding to the various positions of said auxiliary switch, and means responsive to the operation of said auxiliary switch to one of its said predetermined positions for causing said transmitter to transmit the coded signal corresponding to the said position.

24. In a combined telephone and signalling system, an exchange, a group of subscribers' lines extending to said exchange, means including a plurality of automatic switches for establishing telephone connections between said lines, an auxiliary automatic switch having positions individually corresponding to individual ones of said lines, holding means arranged to be operated in response to the operation of one of said plurality of switches to a predetermined position, means responsive to the operation of said holding means for causing said auxiliary switch to operate to one of its positions, a signal transmitter adapted to transmit coded signals of different characteristics individually corresponding to the various positions of said auxiliary switch, and means responsive to the operation of said auxiliary switch to one of its said predetermined positions for causing said transmitter to transmit the coded signal corresponding to the said position.

25. In a combined telephone and signalling system, an exchange, a group of subscribers' lines extending to said exchange, means including a

plurality of automatic switches for establishing telephone connections between said lines, each of said switches being arranged to be taken for use by a calling one of said lines and being operative to a plurality of positions, holding means arranged to be operated in response to the operation of one of said switches to a predetermined position, a relay individually associated with each of said lines and operative in response to the operation of said holding means only when the associated line is responsible for the operation of said holding means, an auxiliary automatic switch having positions individually corresponding to said relays, means responsive to the operation of one of said relays for causing said auxiliary switch to operate to the one position corresponding to said one relay, a signal transmitter adapted to transmit coded signals of different characteristics individually corresponding to the various positions of said auxiliary switch, and means responsive to the operation of said auxiliary switch to said one of its positions for causing said transmitter to transmit the coded signal corresponding to said one position.

26. In a combined telephone and signalling system, an exchange, a plurality of subscribers' lines extending to said exchange, a telephone including an impulsing device connected to one of said lines, an automatic switch adapted to be taken for use by said one line in response to the initiation of a call at said telephone, said switch being operative to a plurality of positions in response to impulses transmitted thereto from said impulsing device, a relay associated with said one line, means responsive to the operation of said switch to a predetermined position for operating said relay, and signalling means responsive to the operation of said relay for transmitting a signal identifying said one line.

27. In a combined telephone and signalling

system, an exchange, a plurality of subscribers' lines extending to said exchange, a telephone including an impulsing device connected to one of said lines, an automatic switch adapted to be taken for use by said one line in response to the initiation of a call at said telephone, said switch being operative to a plurality of positions in response to impulses transmitted thereto from said impulsing device, holding means operative in response to the operation of said switch to a predetermined position, a relay associated with said one line and operative in response to the operation of said holding means, and signalling means responsive to the operation of said relay for transmitting a signal identifying said line.

28. In a combined telephone and signalling system, an exchange, a plurality of subscribers' lines extending to said exchange, a telephone including an impulsing device connected to one of said lines, an automatic switch adapted to be taken for use by said one line in response to the initiation of a call at said telephone, said switch being operative to a plurality of positions in response to impulses transmitted thereto from said impulsing device, holding means operative in response to the operation of said switch to a predetermined position, a relay associated with said one line, a normally open operating circuit for said relay, means comprising said holding means for completing said circuit, a normally open holding circuit for said relay, signalling means responsive to the operation of said relay for transmitting a signal identifying said one line, and means included in said signalling means for completing said holding circuit, whereby said signal is completely transmitted irrespective of the condition of said holding means.

CLARENCE E. LOMAX.

JOHN H. VOSS.
